HALL SWITCH & SIGNAL COMPANY, A CORPORATION OF MAINE.

SELECTIVE SIGNALING SYSTEM.

1111 792

Specification of Letters Patent. Patented Sept. 29, 1914.

Original application filed March 28, 1910, Serial No. 552,054. Divided and this application filed March 8, 1911. Serial No. 613,011.

To all whom it may concern:

Be it known that I, EDWIN R. GILL, residing at Yonkers, in the county of Westchester and State of New York, have invented certain new and useful Improvements in Selective Signaling Systems, of which the following is a specification.

This invention relates broadly to signaling systems, and specifically, to such systems as are particularly adapted for train dispatching work, the present application being a division of my application Serial No. 5, 654, filed March 28th, 1910, selective signaling systems.

One of the important objects of the invention is to increase and vary the character of service which may be had in connection with a system of metallic conductors which form the circuit of the telephone line.

Another "sign" is to so construct and connect a pair of conductors forming opposite sides of a loop with a third conductor which may be ground, that selective signaling, telephone and telegraph apparatus may be operated independently and independently between distinct stations without being confused.

Another object is to so arrange the plates, supports and various auxiliary structures that explosive sounds produced by the operation of the surface electrodes upon the transversely magnetized core the conductivity of which is increased, will be prevented from being transmitted through the metal core.

The incentive considerably consists in the features of the function, combination of the 46 merits and arrangement of parts by the latter described and the scope of the application of which will be indicated in the append-

The accompanying drawing illustrates
45 diagrammatically a preferred embodiment
of my present invention.

Passing into this diagram, A denotes a calling station and B one of various called stations which may be arranged along a telephone line, the opposite ends of which are indicated at 1 and 2. Located, in the present instance, in bridge of this telephone line in each of the sections A and B is telephone apparatus denoted generally by

the numerals 3 and 4 respectively, each apparatus comprising the usual transmitter, receiver, primary, secondary and receiver hook, the latter making and breaking the usual connections whereby the local batteries are applied. Condensers as at 3 and 3 are interposed in the bridge of the telephone apparatus 3 and 4.

located in bridges 7 and 8 of the telephone line and flanked on either side by inductance or choke coils 10 and 11 are selective detectors 12 and 13 respectively. Although any approved type of selective apparatus may be employed in this relation, the type preferred is that disclosed in Letters Patent of the United States No. 906,525, issued to me on December 1, 1908.

21. Testimony on telephone switch key of telephone illustrating its use when applied to the Series 100. It is well known that when a switch is actuated a current is made for many distributor lines, and it is sufficient for the purposes of the present specification to state that this sending key apparatus is provided with a plurality of keys such as is of a own as in 22, each of which when operated is adapted through apparatus presently to be described to cause a particular series of coded impulses to be impressed upon the sending line, and it will be further understood that there is a key provided for each of the various stations along the line and that selective apparatus at each station is responsive to a particular series of coded impulses which are caused to be impressed upon the line by the key provided for that station in the calling station.

As shown herein, the various keys in the

apparatus 21 are adapted to close a circuit including the battery 23, wires 24, 25, 26, coil 27 of the relay denoted generally at 28, and wire 30 which leads to the opposite side 5 of the battery 23. When the circuit just described is closed by one of the keys the battery 23 is applied thereto, relay 28 operated and the armature 31 thereof caused to engage the contact 32 whereby the battery 10 33 is applied to the main line through the inductance coil 34. A similar inductance coil 35 is provided between side 2 of the line and the armature 31 of the relay 28 and a condenser 36 is interposed between the 15 side 1 and said armature.

Each of the selectors 12 and 13 is provided with a pair of coils 37, 38, and 40, 41 respectively, said coils being connected by wires 42 and 43.

20 Referring now to the part of the system provided in the station A, a wire 44 leads from the wire 42 which is located in the center or balanced part or bridge of the selector, said wire 44 leading to the wire 45 which in turn leads to the wire 46. Wire 46 leads to contact member 14, whence the circuit extends through contact 15, wire 47, electric call bell 16, wire 48, wire 49 and wire 50 to the ground 51. Thus it will be understood that when the selector 19 closes the circuit at 14 and 15, the call bell 16 will be operated by the current supplied from battery 23 which is taken off intermediate the coils 37, 38 by the wire 44. The circuit 25 then extends through wire 45, wire 46, contacts 14, 15, wire 47 to the call bell 16; then through wires 48, 49 and 50 to ground 51, then to ground 69, inductance coil 77, battery 23, thence through wire 30, coil 27, 30 wire 26, contact 103, switch arm 103, thence through the bridging wire 101 to the opposite sides of the line, thence through the inductance coils 10 and 11 and coils 37 and 38.

If the switch arm 103 is swung into engagement with the contact 100 another current will pass through the coil 98, contact 100, switch arm 103, and the bridging wire 101 to the opposite side of the line, instead of by way of the coil 27 as has been above described. In a similar manner call bell 20 is actuated by current taken off from wire 43 intermediate coils 10 and 11 by wires 52, 53, contact member 17, contact member 18, wires 54, 55, 56 and ground 57.

55 58 denotes generally a telephone apparatus which may be located in the calling station A, and 60 similarly denotes another telephone apparatus which may be located in the called station B. Leading to the secondary of the telephone apparatus 58 is a wire 61 provided with the contact 62, which when the receiver is off the hook contacts with the wire 45. Wire 61 is provided with a condenser 63 and after passing through 60 the receiver 64 and secondary is grounded

to the wire 50. Connected in shunt about the telephone receiver 64 is a choke coil 65 provided with an adjustable core 66, the function of this coil being to allow currents other than the high frequency speaking currents to pass about the receiver, thus protecting the same against noises. 70

Leading to the telephone receiver 67 of the apparatus 60 is a wire 68 which makes electrical connection with the wire 52 when the receiver is off the hook, wire 68 passing through the condenser 70 the receiver 67 and secondary to ground. Shunted about the receiver 67 is a wire 71 which includes an inductance coil 72 which is provided with an adjustable core 73, the function of which is similar to the coil 65 which has been heretobefore described. 75

80 Leading from the wire 45 is a wire 74 provided with contact member 75 which operates with the contact 76 to close the circuit leading from the wire 42 intermediate the coils 37, 38 to ground. Contacts 75 and 76, when in engagement, will close a circuit through ground 69 and inductance 85 coil 77 to actuate the relay 28 whereby the battery 33 is applied to the line and the selector operated thereby in accordance with the particular series of code impulses produced by the contacts 75 and 76. It will 90 be understood that for the contact 75 and 95 76 might be substituted an automatic sender key apparatus such as is illustrated at 21. Similarly, contacts 78 and 80 in the station B may be actuated to close a circuit through ground which will actuate the relay 28 to apply the battery 33 to the line whereby the selective apparatus will be operated. 100

Referring to the apparatus located in the station A, 81 is a wire which leads to a relay coil 82 and leading from this coil is a wire 83 which terminates in a contact member 84, and with which contact member 86 operates a switch arm 85 connected with the telegraphic sender key 86. 105

86 represents the local battery for the telegraphic apparatus and leading from this battery to the wire 50 is a wire 88, the wire 90 which leads to the battery being provided with the contact 91 which when the sender 110 key 86 is engaged therewith, the switch arm 85 having been engaged with the contact 84, closes a circuit through ground which will 115 actuate the armature 92 of the relay 82 and also the armature 93 of the telegraphic relay 120 94 in station B assuming, of course, that the telegraphic switch arm 85 has been engaged with the contact 96.

In order that the telegraph operator at either of the keys 86 or 97 may communicate 125 telegraphically with the train despatcher in the station a relay is provided at 98, one terminal of the coil of which is connected with the wire 30, and the other terminal with a contact point 100. Located in a bridge 101 130

of the main line and provided with the inductance coils 102 is a switch arm 103 which is adapted to coöperate with any of the contacts 100, 104 or 105. Contact 104 is a dead 5 contact, and contact 105 is connected with a wire 106 which, in turn is connected with the wire 26.

Having thus described the construction, arrangement and relation of the various instrumentalities which comprise this embodiment of my invention, the operation thereof may now be understood: When the operator in the calling station is desirous of calling one of the distant stations he simply operates 15 one of the sender keys 22 thereby closing the circuit which operates the relay 28, as has been hereinbefore described, the armature 31 engaging the contact 32 whereby the line battery 33 is applied thereto as will be understood. A particular series of codal impulses having been impressed upon the line the selective apparatus responsive thereto is 20 actuated, say for instance, that located in the station B. Contact 17 is thereby caused to engage with contact 18 whereby the call bell 25 will be operated. This will inform the operator in station B that the operator at the main line station wishes to communicate with him and telephonic communication will 30 then be had by means of the telephone apparatus 3 and 4, the metallic circuit being utilized for this purpose. When an operator in any of the stations desires to use the telephones denoted at 58 or 60, either of the 35 buttons 75 or 78 may be caused to engage with its coöperating contact, whereby a circuit will be closed through ground to operate the relay 28 and apply the battery 33 to the line whereby the sending of the proper 40 series of impulses will operate the selective apparatus at the station called to close the circuit through the calling signal. Telephone communication may then be had, say between the telephone apparatus 58 and 60, the sides 1 and 2 of the line acting as a common conductor and coöperating with ground to establish the telephone circuit. When it is desired to utilize 45 the system for telegraphic purposes, the station desired is called in the usual manner as by operating the contacts 75 and 78 whereby the local call signal at station B will be 50 operated. The switch arms 85 and 95 are then operated to engage respectively with the contacts 84 and 96 whereby the telegraphic sender key 97 will be caused to operate the relay 92. The relay 94 will thereby be operated by means of the circuit comprising sides 1 and 2 of the line as a common conductor and ground. When key 97 is operated, switches 83 and 93 having 55 been closed, relays 82 and 94 will be operated by the following current: beginning with the battery 37 through key 97, switch arm 95, contact 96, relay 94, wires 52 and 43, coils

40 and 41, coils 10 and 11, to the sides 1 and 2 of the line; thence through coils 10 and 11 of the selector in the station A, coils 37, 38, wires 42, 44, wire 81, relay 82, wire 83, contact 84, switch arm 85, key 86, wires 49 and 50 to ground; then through ground 57 and wire 56 back to battery 37. When either of the operators at keys 86 and 97 wishes to communicate with the train despatcher, a signal may be transmitted selectively which 70 will notify the train despatcher who will then move switch arm 103 to contact 100. This will permit relay 98 to be operated without effecting an operation of relay 28.

By the arrangement of the various instrumentalities as above described the telephone apparatus at two or more of the bridging stations may be in use at the same time that two or more grounded telephones are being used without interfering with 80 each other. Or two or more of the bridging stations may be in use and at the same time local grounded stations may be in telegraphic communication with each other without interfering. So also may bridging 85 telephones be in use while calling is going on for either of the grounded or bridging stations without interference. It will also be noted that when the local grounded stations are not in use the line is free from any 85 disturbance which might arise through such grounded conditions. Any difficulty which might be encountered by using such grounded circuits such as noises produced by induction in neighboring circuits may be substantially eliminated by providing the choke coils around the receivers 64 and 67 as heretofore described.

The train despatcher at the central office, when he wishes to control the calling, independent of the local grounded or bridging stations, may move the switch arm 103 to contact 104, and thereby break the circuit of the battery through the central relay to ground thereby, making it inoperative to 110 ground at local stations. The various retard coils across the metallic pair of telephone line are for preventing the telephone sound waves from crossing. Retard coils 102 are employed for reducing the noises 115 reaching the telephone line through the grounded contacts and the coils 34 and 35 together with the condenser 36 are used for applying the battery pulsations to the line silently.

The use of selectors for calling enables the operators to call each other or be called selectively and only when the grounded circuits are in use are those circuits operative or connected with the line. In other 125 words the line, when grounded stations are not in use, is always clear for testing or other purposes.

It will be noted that the coils of the selectors perform a double function in that they 130

perate as inductance coils for the grounded circuits and reduce the noises in the telephones therein. And it should be further noted that since the grounded circuits are taken off the bridge or balanced part of the selector the operation of the latter are in no wise affected.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense. It is also to be understood that the language used in the following claims is intended to cover all of the generic and specific features of the invention herein described and all statements of the scope of the invention, which as a matter of language, might be said to fall therebetween.

Having thus described my invention, what I claim as new and desire to secure by Letters-Patent, is:

1. In a system of the class described in combination, a line comprising a metallic pair, selective signaling means in bridge of said line, means for impressing electrical impulses over said metallic pair in opposite said selective organs, a ground connection for the opposite sides of said line, and means in said ground connection for controlling said means.

3. Is a system of the class described in combination, a line comprising a main pair, a plurality of selectors connected in bridge of said line, a ground connection for the opposite sides of said line near each selector, a source of current supply for said line, means for impressing signaling impulses from said source of supply to said line to operate said selectors, and a plurality of means, one at the central station and another in a ground connection adapted independently to control the operation of said selectors.

3. In a system of the class described, in combination, a line comprising a metallic pair, a plurality of selectors in bridge of said pair, a plurality of local signaling devices each of which is provided with a circuit adapted to be closed by one of said selectors, means associated with said line for operating said selectors, a ground connection common to the opposite sides of said line near each selector, and means associated with said ground connection for controlling the operation of said means.

4. In a system of the class described, in combination, a line comprising a bistable pair, a selector comprising a pair of nodes connected in bridge of said line, a connector leading from a point intermediate said selector

1 to ground, and means in said ground connection adapted to control the selectors.

5. In a system of the class described, in combination, a line comprising a pair of metallic sides, a selector comprising a pair of coils connected in bridge of said line, a normally open connection leading from a point intermediate said coils to ground, and means for closing said ground connection.

6. In a system of the class described, in combination, a line comprising a metallic pair, a plurality of selectors, each of which is located in an independent bridge of the line, a connection leading from opposite sides of said line through the coils of each of said selectors to ground, and means in each of said ground connections adapted to control the operation of said selectors.

6. A system of the class described, comprising in combination, a line comprising a metallic pair, a plurality of selectors each of which is located in an independent bridge of the line, a ground connection between each of said bridges and means in each of said ground connections adapted to control the operation of said selectors. 59

8. To a system of the class described, in combination, a line comprising a metallic pair, a plurality of selecting devices in bridge circuit line, a ground connection for the opposite ends of said line near each selector and a circuit of means, one at the central station and another in each ground connection, arranged independently to control the connection of said selector.

9. In a system of telegraphy described, in 1901, in combination, a line comprising a metallic wire, a plurality of selector contacts connected in parallel or said path, a ground connection for the opposite sides of said line near each selector, a source of current supply for said line, a relay for impressing signaling impulses from said source of supply to said line and a plurality of means, one at the central station and another in each ground connection, adapted independently to control the operation of said relay.

10. In a selective signaling system, the combination with line wires having a sending station and a plurality of way stations connected therewith, of a selector in bridge 115 of the line wires at each of said way stations responsive to current impulses, a source of calling current, an impulse relay for connecting said source of current with said line wires, and circuit closing means and connections at said sending and calling stations for completing an operating circuit for said impulse relay over the two line wires in parallel to ground. 120

Fig. 2. Telephone selector system comprising a telephone circuit, a plurality of sub-station telephone jacks, a switch device, the main circuit and a telephone selector connection.

to ground, a signaling battery located in the central office in a normally open bridge connection across the main conductors, a connection from the main circuit to ground at 5 the central office, a source of electrical energy and an electro-magnetic device in said last named ground connection and means whereby the normally open bridge connecting the signaling battery is closed whenever 10 said electro-magnetic device is energized.

12. In a selective signaling system, the combination with line wires having a sending station and a plurality of way-stations connected therewith, of a selector in bridge 15 with the line wires at each of said way-sta-

tions responsive to current impulses, a source of calling current, an impulse relay at the sending station for connecting said source of current with said line wires and circuit closing means at said way-stations for completing an operating circuit of said impulse relay over the two line wires in parallel to ground. 20

In testimony whereof I have hereunto set my hand in the presence of two witnesses. 25
